US00D691140S

(12) **United States Design Patent**
Huang

(10) **Patent No.:** **US D691,140 S**
(45) **Date of Patent:** **** Oct. 8, 2013**

(54) **USB HUB**

(71) Applicant: **Delta Electronics (Thailand) Public Co., Ltd.**, Samutprakam (TH)

(72) Inventor: **Jui-Ching Huang**, Amphur Muang (TH)

(73) Assignee: **Delta Electronics (Thailand) Public Co., Ltd.**, Amphur Muang (TH)

(**) Term: **14 Years**

(21) Appl. No.: **29/439,668**

(22) Filed: **Dec. 13, 2012**

(51) LOC (9) Cl. **14-02**

(52) U.S. Cl.

USPC **D14/433**

(58) **Field of Classification Search**

USPC D14/356, 432-434, 453, 454, 511, D14/203.8, 209.1, 238.1, 240, 125; 439/638, 439/928, 105, 502; 710/303, 304; 361/679.41, 361/679.55, 679.56; D13/110, 133, 146
